[57] CLAIM

The ornamental design for a personal digital electronic device, as shown and described.

DESCRIPTION

FIG. 1 is a perspective view of the personal digital electronic device of the present invention;

FIG. 2 is left elevation of the personal digital electronic device of FIG. 1;

FIG. 3 is a plan view of the personal digital electronic device of FIG. 1;

FIG. 4 is a rear elevation of the personal digital electronic device of FIG. 1;

FIG. 5 is a right elevation of the personal digital electronic device of FIG. 1;

FIG. 6 is a plan view of a second embodiment of the personal digital electronic device of FIG. 1 wherein the undisclosed views are understood to be identical in appearance to those of the first embodiment; and,

FIG. 7 is a perspective view of the personal digital electronic device of FIG. 6.
